UNITED STATES PATENT OFFICE.

GASTON CHANDON DE BRIAILLES, OF PARIS, FRANCE.

ELECTROLYTIC APPARATUS FOR THE MANUFACTURE OF NITROCELLULOSE.

No. 874,564.

Specification of Letters Patent.

Patented Dec. 24, 1907.

Application filed March 10, 1906. Serial No. 305,345.

To all whom it may concern:

Be it known that I, GASTON CHANDON DE BRIAILLES, gentleman, citizen of the French Republic, residing at Paris, in the Department of the Seine, France, have invented cer-

tain new and useful Improvements in Electrolytic Apparatus for the Manufacture of Nitrocellulose, of which the following is a specification.

10 In the manufacture of nitrocellulose for the manufacture of smokeless powder for war, sporting, and mining purposes, for celluloid, silk, straw, feathers, artificial horse-hair and all such products having nitrated cellulose as a base, the workmen are exposed to the absorption of poisonous and suffocating gases; their clothes as well as a number of surrounding objects are attacked by these gases. Further, sulfuric acid and nitric acid 20 employed for this manufacture become undesirable for use a second time.

The quantity of cellulose nitrated in one operation has the effect of hydrating the mixture of acids, these being no longer fit for 25 nitrating a fresh quantity of cellulose. Generally these are added to other quantities of these acids in a state of concentration, which increases the net cost and indefinitely increases the volume of liquid employed. In 30 applying this electrolytic concentration of acids for the nitration of cellulose all dangers of manipulation are avoided, also all losses by hydration by damp air and the same acids can be used almost indefinitely save that 35 part of the nitric acid passing into combination with the nitrated cotton.

The accompanying drawing is a vertical section of a receptacle for nitrating cellulose.

Each receptacle employed is preferably 40 cylindrical and formed of strengthened glass. The closure at the upper part is effected by a glass cover or stopper. This reservoir is furnished at its convex base with a branch 8, and a glass delivery valve 9. Towards the 45 middle of the height of the reservoir on the interior of the wall a circular projection 10, is provided, strong enough to support a porcelain partition 11. Upon this partition is perforated with a number of holes 12, is 50 lightly heaped the cellulose 13, to be nitrated. The reservoir is filled with a suitable mixture of concentrated sulfuric acid and ordinary nitric acid.

A thermometer 14 is placed vertically in 55 the chamber 15 formed in the lower part of the reservoir. The reading of this and any

other instrument employed in the operation and located within the receptacle can be made without any necessity of opening the reservoir.

A gilded platinum positive electrode 16 is arranged against the lower face of the porcelain diaphragm. In its inactive part it is isolated from the acids by a small glass tube which has been cast and soldered to the stem 60 on the same metal conductor.

The platinum negative electrode 17 rests on the bottom of the reservoir at the part where the density of the nitric acid is lowest. The electrodes are platinum or gilded platinum wire drawn out. They thus constitute rheostats to moderately heat the liquid. The active surface of the negative electrode ought to be smaller than that of the positive electrode so that the quantity of nitric acid 70 involved will be the least possible.

In order to obtain a good nitration of the cellulose, it is necessary to have in solution a small quantity of nitrous acid, which is produced by the action of the hydrogen in contact with the negative electrode and the nitric acid. An excess of nitrous acid can be detected by the coloration imparted to the colorless liquid mass. In this case the surface of the negative electrode ought to be reduced or it ought to be enveloped with asbestos cloth or spun glass which reduces the diffusion of the acids and makes the action of the occluded gases predominate. The immersed cellulose in the mixture of the two 80 acids will be found to be nitrated in about 3 or 4 hours if the temperature does not fall below 30° C. In any case, it ought not to exceed 40° C. In order to moderate the heating action resulting from the passage of the 85 current, the electric current consumption can be reduced, but this will reduce the speed of concentration.

The nitrated cellulose can be washed without opening the receptacle and without allowing any deleterious gases to be liberated. To attain this result the exhausted liquid can be drawn off by means of a suction acid pump attached to the delivery tube. Then by the aid of porcelain disk 18 forming a piston mounted on a neck of the same material adapted to engage in a flexible stopper 19 of india-rubber a strong force can be exercised on the cellulose in order to expel the absorbed acids. When one has drawn off by the pump 100 all the liquid which passes by the delivery tube, water is fed into the two chambers of 105

the receptacle, the nitrated cellulose is thus washed until it no longer evolves vapor. The receptacle is then opened and the cellulose is submitted to further washings in the 5 open air.

It is necessary before proceeding to a fresh operation to make the pump draw off all the washing water which adheres to the bottom and the walls and in case of need to flow back 10 into the receptacle the air compressed by the pump. A fresh charge of cellulose to be nitrated is placed on the porcelain diaphragm, the receptacle is closed and the exhausted acids added to a suitable quantity of ordinary 15 nitric acid is delivered by the pump. The current is switched on in order to produce the desired concentration. An acidometer may be used to indicate the degree to be attained. All the receptacles of the same 20 installation are grouped in series and are traversed by the same current.

Having now particularly described and ascertained the nature of my said invention and in what manner the same is to be performed, I declare that what I claim is:

1. The combination with a receptacle, of a 25 perforated diaphragm dividing it into upper and lower chambers, positive and negative electrodes in the lower chamber, and a drain 30 pipe leading from said lower chamber.

2. The combination with a receptacle, of a

perforated diaphragm dividing it into upper and lower chambers, a positive electrode located adjacent to the underside of the diaphragm, and a negative electrode located 35 near the bottom of the receptacle.

3. The combination with a receptacle, of a perforated diaphragm dividing it into upper and lower chambers, and electrodes of gilded platinum wire located in the lower chamber. 40

4. The combination with a receptacle, of a perforated diaphragm dividing it into upper and lower chambers, wire electrodes in the lower chamber, and a piston normally placed at the top of the upper chamber, and means 45 for operating said piston from outside of the receptacle.

5. The combination with a receptacle, of means adapted to retain a charge of cellulose in the upper part of the same, means for conveying a current of electricity into the liquid contents of the lower part of said receptacle, and means for compressing the cellulose to extract the liquid therefrom. 50

In testimony whereof I have hereunto set 55 my hand in presence of two subscribing witnesses.

GASTON CHANDON DE BRIAILLES.
